SWING

William Harold Nicholson, Woodbury, N. J.

Application January 23, 1948, Serial No. 144,003

Term of patent 14 years

(Cl. D15—8)

To all whom it may concern:

Be it known that I, William H. Nicholson, a citizen of the United States of America, residing at Woodbury, in the county of Gloucester and State of New Jersey, have invented a new, original, and ornamental Design for Swing, of which the following is a specification, reference being had to the accompanying drawing, forming a part thereof.

The single figure is a perspective view showing a side and one end of a swing embodying the new design.

The side and end not shown are the same as those illustrated in the drawing figure.

The dominant feature resides in the portions shown in full lines.

What is claimed is:

The ornamental design for a swing, as shown and described.

WILLIAM HAROLD NICHOLSON.
